UNITED STATES PATENT OFFICE.

BENJAMIN F. BUTLER, OF LOVELAND, IOWA.

HEATING-FURNACE.

1,184,165.

Specification of Letters Patent. Patented May 23, 1916.

Application filed June 8, 1915. Serial No. 32,888.

To all whom it may concern:

Be it known that I, BENJAMIN F. BUTLER, a citizen of the United States, residing at Loveland, in the county of Pottawattamie and State of Iowa, have invented a new and useful Heating-Furnace, of which the following is a specification.

The present invention appertains to hot air furnaces, and aims to provide a novel and improved heating furnace of that type.

The invention has for its object the provision of a hot air furnace of unique construction, whereby the fresh air is taken through hollow or tubular grate bars, so that the fresh air will cool the grate bars, and furthermore the fresh air will be given an initial heat at the same time.

Another object of the invention is to so construct and assemble the component parts of the furnace, that the desired results will be carried out in a most practical and efficient manner.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:—

Figure 1 is a vertical central section of the improved furnace. Fig. 2 is a fragmental view of the furnace, looking from the rear. Fig. 3 is a horizontal section taken on the line 3—3 of Fig. 1.

In carrying out the invention, there is provided an inner upright cylindrical drum 1 having the upper combustion chamber 2 therein, the fire pot 3 between its upper and lower ends, and the ash pit 4 at its lower end and below the fire pot. The drum 1 has a rearwardly or laterally projecting outlet sleeve 5 adjacent its lower end and communicating with the ash pit 4, and is provided with a rearwardly or laterally projecting sleeve 6 adjacent its upper end and communicating with the combustion chamber 2.

A discharge pipe 7, leading to the chimney, has its lower end slipped into engagement with the lower outlet sleeve 5, and is provided above its lower end with a branch

8 slipped into engagement with the upper outlet sleeve 6 of the drum. A damper 9 is pivoted within the outlet sleeve 6 to control the outlet of the gases through the said sleeve, and a damper 10 is pivoted within the pipe 7 between the branch 8 and lower end of the pipe, for controlling the outlet of gases through the outlet sleeve 5.

The front wall of the drum 1 has an opening 11 immediately above the fire pot 3 communicating with the combustion chamber 2, and said front wall of the drum is provided with an ash opening 12 below the fire pot 3 and communicating with the ash pit 4.

A jacket or casing 13 incloses the drum 1, and the upper end of the upright cylindrical jacket 13 is provided with suitable air outlets 14 for delivering the hot air to the registers, or the like.

A casting or member 15 is secured to the front wall of the drum around the opening 11, and extends through the front wall of the jacket 13, and suitable doors 16 are hinged to the outer edge portion of the casting 15 for normally closing the opening through the casting, although one or both of the doors 16 may be opened for admitting air into the drum, or for enabling the coal or other fuel to be shoveled into the fire pot.

A rectangular casting 17 extends through a rectangular opening in the front wall of the jacket 13 below the casting 15, and embodies a top, bottom and sides having flanges at their rear edges attached to the drum around the opening 12 thereof. The casting has a front plate overlapping and attached to the jacket, and has a horizontal partition between the top and bottom to provide an air inlet chamber 19 above the partition. Said front plate has an upper opening 20 above the partition, and a lower opening below said partition, the opening 12 of the drum also being located below said partition. As ash door 18 is hinged at one end to the outer side of the front plate of the casting 17 at one side of the lower opening to close said opening, and an air controlling door 21 is hinged to the inner side of said front plate above the upper opening thereof, to swing downwardly against the front plate to close the opening 20, and adapted to be swung upwardly against the top of the casting 17, as illustrated in Fig. 1. The free edge of the door 21 is connected by means of a link 22 with the upper edge

of the ash door 18 adjacent the hinge of the ash door, whereby when the ash door 18 is swung to closed position, the link 22 swings the air controlling door 21 rearwardly and upwardly against the top of the casting 17, while when the door 18 is swung open, the link 22 pulls the door 21 downwardly and forwardly to close the opening 20.

10 The grate embodies a plurality or series of parallel rearwardly inclined tubular or hollow grate bars 23 extending through the front and back walls of the drum 1. The lower or forward ends of the grate bars 23 are received by the chamber 19 whereby fresh air may flow upwardly through the grate bars 23 from the chamber 19 into the air space between the drum 1 and jacket 13.

As a means for supporting the upper or 20 rear ends of the grate bars 23, a casting 24 is secured to the back wall of the drum 1 above the outlet sleeve 5, and a plate 25 is secured in any suitable manner to the casting 24. The rear or upper ends of the grate 25 bars 23 are engaged through the plate 25, and nuts 26 are threaded upon the rear end 30 portions of the grate bars 23 and bear against the outer and inner sides of the plate 25, for adjustably holding the grate bars 23 in position.

The walls of the fire pot 3 are preferably lined with fire brick or other refractory material 27, the fire brick or lining 27 being supported by the grate bars 23.

35 A siphon pipe or tube 28 which is disposed exteriorly of the drum 1 and within the jacket 13 has its upper end engaged to the center of the dome shaped upper end of the drum 1, and has its lower end engaged 40 through one side of the drum 1 below the grate to communicate with the ash pit 4.

In operation, when an updraft through 45 the grate is desired, the damper 9 is opened, and the damper 10 is closed, whereby the products of combustion are constrained to rise upwardly through the outlet sleeve 6 into the pipe 7. Air is admitted through the ash door 18 so as to pass upwardly through the grate and coals, whereby the 50 products of combustion rise in the combustion chamber 2 for heating the walls of the drum 1, so that the air between the drum and jacket is properly heated. The cooler air at the upper end of the drum 1 is siphoned down through the pipe or tube 28 into the ash pit below the grate whereby it 55 will be drawn upwardly through the grate and coals. This prevents the cooler air being trapped at the upper end of the drum, and the drum is therefore properly heated 60 throughout its upper portion, for properly heating the air between the drum and jacket. The air to be heated is drawn inwardly through the chamber 19 and tubular grate 65 bars 23, and will flow into the air heating

chamber or space between the drum and jacket from the rear ends of the grate bars. The heated air rises and flows outwardly through the outlets 14 of the jacket. The fresh air in flowing into the tubular grate 70 bars will serve to cool the said grate bars, which is desirable, and furthermore, the fresh air will be given an initial heat, to increase the efficiency of the furnace. When the door 18 is opened for taking out the 75 ashes, the door 21 will be closed, and this will prevent the dust from being drawn into the air heating chamber through the chamber 19 and grate bars 23, while the ashes are being removed, but as soon as the ash door 80 is again closed, the door 21 will be opened to allow fresh air to again flow into the jacket. The grate bars being inclined rearwardly tend to cause the coals to shift forwardly within the fire pot, which will facilitate the falling of the ashes through the grate, and furthermore, the coals will be worked forwardly so that the new coals in being shoveled through the opening 11 will be properly received at the rear or upper portion of the grate. The inclination of the grate bars 23 is also of advantage since the heated air within the grate bars will rise properly into the heating chamber within the jacket. When a downdraft is desired, 85 the damper 9 is closed, and the damper 10 is opened, so that the products of combustion are constrained to pass downwardly through the outlet sleeve 5 into the pipe 7. One of the doors 16 is opened to admit air 90 into the combustion chamber 2 and fire pot 3, whereby the air will pass downwardly through the coals and grate. The air in being drawn downwardly through the coals, will reduce to a minimum, the clinkering 95 of the coal and ashes, and furthermore, the products of combustion which naturally tend to rise within the combustion chamber 2, will be caught and carried downwardly with the air through the coals. The heated coals will thus cause the soot and 100 heavier particles of the products of combustion to be consumed, whereby the heavy or dense smoke is eliminated, and a saving 105 of fuel accomplished.

110 Having thus described the invention, what is claimed as new is:

A hot air furnace embodying a drum, a jacket inclosing the same, there being an air heating chamber between the drum and jacket, a rectangular casting extending through the jacket and including a top, bottom and sides having flanges at their rear edges attached to the drum, the casting having a front plate overlapping and attached 120 to the jacket, said casting also having a horizontal partition between the top and bottom to provide an air inlet chamber above said partition, tubes extending through the drum from said air inlet chamber to the air 125 130

heating chamber, said front plate having an upper opening above and a lower opening below said partition, the drum having an ash opening below said partition, an ash
5 door hinged to the outer side of the front plate at one side of said lower opening thereof to close said opening, an air controlling door hinged to the inner side of said front plate above the upper opening
10 thereof, and a link connecting the free edge of the air controlling door and the upper

edge of the ash door adjacent the hinge of the ash door, whereby when the ash door is closed and opened, the air controlling door is opened and closed, respectively. 15

In testimony that I claim the foregoing as my own, I have hereto affixed my signature in the presence of two witnesses.

BENJAMIN F. BUTLER.
